IRVIN E. BARRICKLOW, OF SAN FRANCISCO, CALIFORNIA.

CARBURETER.

1,312,468.

Specification of Letters Patent.

Patented Aug. 5, 1919.

Application filed October 18, 1917. Serial No. 197,233.

To all whom it may concern:

Be it known that I, IRVIN E. BARRICKLOW, a citizen of the United States, residing at the city and county of San Francisco and 5 State of California, have invented new and useful Improvements in Carbureters, of which the following is a specification.

This invention relates to a carbureter for internal combustion engines; and one of the 10 objects of the invention is to provide a simple and effective construction which can be used with gasoline or with lower grade fuels, such as distillate, kerosene and the like, or in which gasoline may be employed 15 for starting the engine and the lower grade fuel for running the engine under load when it has been sufficiently heated. Another object of the invention is to provide means operable in unison with the throttle 20 valve for automatically maintaining a predetermined opening between the needle valve and the throttle valve, so that a uniform mixture may be maintained regardless of the opening of the throttle. Another 25 object of the invention is to provide means for supplying water vapor to the explosive mixture and in conjunction therewith to provide means for automatically admitting and varying said mixture in accordance 30 with the speed of the engine or the load thereon. Further objects will hereinafter appear.

The invention consists of the parts and the construction and combination of parts 35 as hereinafter more fully described and claimed, having reference to the accompanying drawings, in which—

Figure 1 is a central, vertical, longitudinal section through the carbureter.

40 Fig. 2 is a side elevation of same.

Fig. 3 is a plan section on line 3—3 of Fig. 4.

Fig. 4 is a plan view of the bottom section of the carbureter.

45 Referring to the drawings in detail, A indicates a cylindrical-shaped casing, the upper end of which is flanged as at 2, to permit it to be secured to the intake manifold of an internal combustion engine. 50 Mounted in the upper end of the casing is a throttle valve, generally indicated at 3, and mounted in the lower end of the casing is a spray nozzle 4 and a needle valve 5.

The spray nozzle is formed in a remov-

able bottom section which consists of a 55 threaded, annular flange 6 adapted to be screwed into the lower end of the casing, as shown at 7. Formed integral with said threaded, annular flange are three arms 8, 9 and 10, and supported by said arms, centrally of the flange, is a center section 11 in which is mounted a plug valve 12. Formed in the upper part of the center section is the spray nozzle 4, and supported by the center section and surrounding the 65 spray nozzle is a cone-shaped cap 13, on the lower end of which is formed an annular flange 14. The cap 13 is spaced from the nozzle as is also the flange 14, thereby forming an air passage which will herein- 70 after be termed the primary air inlet.

The arms 8, 9 and 10 are each provided with a passage (see Figs. 1 and 4); the passage 8 being connected with a source of gasoline supply, the passage in arm 9 with 75 a distillate tank, and the passage in arm 10 with a source of water or water vapor supply, as the radiator of a car. The passages formed in the arms 8 and 9 communicate with the plug valve and as this is provided with one radially disposed passage 15 and a central vertical passage 16, turning of the plug valve, by means of a handle 17, permits either gasoline or distillate to be delivered to the spray nozzle; the discharge 85 through the nozzle being regulated mechanically by the needle valve 5, as will herein- 90 after be described. A stuffing box 18 is preferably placed on the lower end of the plug valve to prevent leakage at this point. 90

The passage formed in the arm 10 does not communicate with the valve but with a vertically extending tube 19 which passes through the flange 14 formed on the cap 13. The discharge of vapor through the pipe 19 95 into the carbureter proper is controlled by a piston valve. This piston valve consists of a cylindrical section 20 and an annular flanged, inturned bottom section 21. This bottom section of the piston valve is normally adapted to seat on the flange 14 and when in this position forms a closure for the passage 19, thereby preventing water vapor from entering the carbureter except when the piston valve is lifted from its seat. 100 The valve is not only retained on the seat by means of its own weight but also by a spring 22 interposed between the valve and

a pair of bracket arms 23 formed in the center portion of the casing. These bracket arms also carry a central hub member 24 which serves as a guide for the stem 5^a of 5 the needle valve.

The construction of the throttle valve and the means operable in connection therewith for automatically regulating the lift of the needle valve form one of the important 10 features of the present invention. This is accomplished as follows: Extending through the center portion of the throttle valve is a shaft 25. This shaft is turnably mounted with relation to the throttle valve and the 15 casing A and is provided for the purpose of supporting the throttle valve and also as a support for a cam 26. Extending half way into the throttle valve and secured thereto in any suitable manner is a sleeve 20 shaft 27, and secured on the outer end of said sleeve shaft is a lever 28 by which the throttle valve is opened and closed from the steering wheel of the car in the usual manner.

25 Formed on the sleeve shaft 27, adjacent to the lever 28, is a bell crank member 29, and carried by each arm of the said member is an adjusting screw 30 which is adapted to engage a stop lug 31 formed on the outer 30 face of the casing A; the crank arms 29, together with the set screws carried thereby, being provided to limit the movement of the throttle valve. The shaft 25, which carries the cam 26, extends beyond the sleeve shaft 35 27 and thereby serves as a support for an arm 32 which permits the position of the cam 26 to be adjusted with relation to the throttle valve. This is accomplished by forming a lug 33 on the throttle valve lever 40 28 which carries an adjusting screw 34. This screw passes through a slot in the arm 32 and a spring 35 interposed between the arm and the lug 33 normally retains the shaft 25 and cam 26 in a fixed and adjusted 45 position with relation to the throttle valve once an adjustment has been made.

The cam 26 is positioned in direct alignment with the stem 5^a of the needle valve and its face is sufficiently wide to engage 50 the same. The larger portion of the cam engages the stem of the needle valve when the throttle valve is practically closed, thereby forcing the needle valve down against the spray nozzle and completely preventing 55 any discharge therefrom. A slight opening movement of the throttle valve, however, turns the cam to a position where the needle valve may open a proportional amount. Further opening of the throttle valve permits a greater opening of the needle valve 60 and it is, therefore, possible to maintain a proportional opening between the needle valve and throttle valve at all times, regardless of their position, which automatically 65 maintains a uniform mixture. The setting

of the cam, which may be adjusted by means of the screw 34, is preferably such that idling position of the throttle valve will permit a slight opening of the needle valve, this being necessary when starting and also 70 when idling.

In actual operation, when it is desired to start the engine, it is only necessary to turn the lever 17, with connected plug valve until connection is made with the gasolene passage 75 formed on the arm 8. Cranking of the car will then create a sufficient suction in the intake manifold and carburetor to permit air to be drawn through the space formed between the arms 8, 9 and 10 and the space 80 formed between the spray nozzle and the cap 13, this air passing under the needle valve in the direction of arrows a lifts it sufficiently to permit the desired amount of fuel to pass through the nozzle. A practically homogeneous and rich mixture is thus obtained as the primary air inlet opening is annular and the needle valve is provided with an annular shoulder 5^b, over 85 which the air and gasolene is evenly distributed. The large annular contact area thus provided permits a better atomization; hence a better mixture is obtained.

Starting of the engine or idling speed requires comparatively little air. This air is, therefore, supplied entirely through the primary air inlet opening and movement or admission of air through the piston valve is not obtained until the speed is increased. The higher suctions produced under greater 95 speeds lifts the valve away from the shoulder or seat 14 against the tension of spring 22 and admits a secondary supply of air between the shoulder 14 and the lower end of the piston valve. A leaner mixture under 100 high speeds may in this manner be obtained while a comparatively rich mixture may be maintained for starting by regulating the position of the cam with relation to the needle valve and the throttle valve. A rich 105 mixture may also be obtained when the engine is running at high speed and under a heavy load by again adjusting the position of the cam. These adjustments, however, are made when the carburetor is first applied 110 to an engine and one setting or adjustment is generally sufficient to regulate the mixture so that it is ideal for different speeds and loads.

The present construction and arrangement of parts permit a compact, simple arrangement which may be easily adjusted for varying conditions and, furthermore, permit an engine to be started on gasolene when cold and to be run on distillate or any 125 other suitable low grade fuel, once the engine has become heated; the change being permitted without stopping the engine as a connection between the dashboard and the lever 17 permits the position of the plug 130

valve to be instantly changed from gasoline to distillate. The water vapor is only admitted when the piston valve opens, or, in other words, when the engine is running 5 under comparatively high speeds or heavy load.

Everything provided is automatic in operation as regards water vapor admission and the regulation of fuel, as the needle 10 valve can only open in proportion to the opening of the throttle. The major portion of the air will at all times pass through the annular primary air opening, and as this is arranged around the spray nozzle a homogeneous mixture is obtained. The wings of 15 the throttle valve are preferably offset with relation to each other, as shown in Fig. 1, to permit the valve to assume an absolutely vertical position when entirely opened.

20 The materials and finish of the several parts of the carbureter may be such as the experience and judgment of the manufacturer may dictate.

I wish it understood that various changes 25 in form, proportions and minor details of construction may be resorted to within the scope of the appended claims and that I do not wish to limit myself to the specific design and construction here shown.

30 Having thus described my invention, what I claim and desire to secure by Letters Patent is—

1. In a carbureter, a needle valve having a stem the upper end of which is free, a throttle 35 valve, a cam connected to the throttle valve and having wiping engagement with the free upper end of the needle valve stem, and a positive connection between the cam and throttle valve having turnable threaded 40 means for adjusting the position of the cam with relation to the throttle valve by mere turning of the threaded means.

2. In a carbureter, a needle valve having a stem the upper end of which is free, a throttle 45 valve having a lever, a cam adjustably connected to the throttle valve and having wiping engagement with the free upper end of the needle valve stem, an arm in connection with the cam, a screw connection between said arm and lever for adjusting the 50 position of the cam with relation to the throttle valve.

3. A carbureter comprising a casing, a spray nozzle mounted in the lower end of 55 the casing, a cone-shaped cap spaced from and surrounding the nozzle forming a primary air inlet, a piston valve slidably mounted in the casing adapted to seat on the cap and to open or close a secondary 60 annular air inlet formed between the cap and the casing, a throttle valve in the casing,

and means for admitting a water vapor to the carbureter, said means controlled by the piston valve for regulating the amount of vapor admitted.

65

4. In a carbureter in combination with a throttle valve and a needle valve, a shaft, a cam on said shaft for operating the needle valve, a sleeve turnably surrounding said shaft, a lever connected to said sleeve to 70 operate the throttle valve, a bell crank member on said sleeve, means engaging each arm of said member to limit the movement of the sleeve, an arm on said shaft to adjust the position of said shaft and thereby that of 75 the cam, an adjusting screw carried by said lever of the throttle valve and having connection with said arm of the shaft, and a spring encircling said screw for holding the shaft and cam in their adjusted position. 80

5. In combination with the throttle valve and the needle valve of a carbureter, a cam for operating the needle valve, a lever for operating the cam, an arm connected to the throttle valve and a screw connecting the 85 arm and lever to effect operation of the cam upon movement of the arm and to enable adjustment of the position of the cam relative to the throttle valve by mere turning of the screw. 90

6. In combination with the throttle valve and the needle valve of a carbureter, a shaft, means operated by said shaft to actuate the needle valve, a lever on said shaft to operate same, a sleeve supporting the throttle valve, 95 an arm connected to said sleeve to operate same, and a turnable threaded connection between said arm and lever to effect adjustment by mere turning of the threaded connection and operation of said needle valve 100 actuating means upon operation of the throttle valve.

7. In a carbureter, a casing, a nozzle in the casing, a cap spaced from the nozzle to form an air inlet and having an outwardly extending flange at its base, a tube in communication with a source of fluid supply and having its upper end extending through said flange, said flange being spaced from the side walls of the casing to allow the passage of 105 air, and a piston valve in the casing engageable with the upper end of the tube to close same and also being engageable with said flange to prevent the passage of air therepast. 110

In testimony whereof I have hereunto set my hand in the presence of two subscribing witnesses.
